TANK FOR STORING AND DISPENSING LIQUID CO₂ OR THE LIKE

Frank S. Wyle, Los Angeles, and James A. Sneller, Palos Verdes Estates, Calif., assignors to Wyle Manufacturing Corporation, El Segundo, Calif., a corporation of California

Filed Jan. 18, 1960, Ser. No. 59,071

Term of patent 14 years

(Cl. D14—3)

FIG. 1.

FIG. 2.

FIG. 3.

FIG. 4.

FIG. 5.

FIG. 6.

FIGURE 1 is a side elevation showing a tank for storing and dispensing liquid CO₂ or the like of our new design;

FIGURE 2 is a side elevation of the opposite side;

FIGURE 3 is a top plan view;

FIGURE 4 is a bottom plan view;

FIGURE 5 is a front view; and

FIGURE 6 is a rear view.

The dominant features of our design are shown in full lines.

We claim:

The ornamental design for a tank for storing and dispensing liquid CO₂ or the like, as shown and described.
